HYDRAULIC DEVICE

Nicolaus Habsch, Wuppertal-Vohwinkel,
GermanyApplication August 24, 1949, Serial No. 112,160
In Belgium September 18, 1948

4 Claims. (Cl. 103—55)

1

This invention relates to a hydraulic device which achieves a very high pressure though a low drop of a river only is available, and particularly to a hydraulic device which is adapted by example for locations where a creek or river in a valley is to be used for feeding water to higher locations or for driving a turbine.

Thus it is one object of the present invention to provide a hydraulic device, the operation of which does not interfere with the water rights of neighbors or land owners on the same river, which is brought about by not using the flowing water, which operates the device, as working water. This object is achieved by using ground water, which may be found in each valley and, thereby, also making possible the operation of several such devices in series from the same creek or river.

It is another object of the present invention to provide a hydraulic device which comprises a balance beam which is pivotally supported and each arm of which carries a water container which is positioned below a water outlet being equipped with a valve controlled by the movement of the balance beam.

It is another object of the present invention to provide a reciprocating balance beam to operate a pump which is fed by example from a well.

It is still another object of the present invention to provide a reciprocating balance beam for operating a pump, each arm of which beam carries a water container, and to provide one single control mechanism for simultaneously feeding the raised water container and discharging the lowered water container.

It is yet another object of the present invention to provide a hydraulic device with a reciprocating balance beam which interrupts the pumping action at the moment when the control mechanism for reversal of movement starts its operation.

It is a further object of the present invention to provide, in a hydraulic device with a reciprocating balance beam, each arm of which carries a water container, means for extending the open period of the valves for feeding and discharging said containers upon accidental or intended high pressure of the pump.

With these and other objects in view which will become apparent from the following detailed description, the present invention will be clearly understood in connection with the accompanying drawings in which,

Figure 1 shows a front elevation of one embodiment of the hydraulic device;

2

Fig. 2 is a front elevation, shown at enlarged scale, of the locking mechanism and in point-dotted lines the over-weight position; and

Fig. 3 is a section along the lines 3—3 of Fig. 1.

5 Referring now to the drawings, the hydraulic device comprises a balance beam 3 which is adjustable as to its length and which is supported by a pivot 4 mounted on a frame 2. Water containers 5 and 6 hang in swinging manner from each end of the balance beam 3. Each one of said containers is equipped with a discharge valve 7. A feed outlet 8 and 9, respectively, leads to the water containers 5 and 6, respectively, depending upon the position of the balance beam 3, which feed outlets are equipped with valves 9 and extend from a feed pipe 10. Each one of the valves 9 is controlled by means of releasing rods 11, against which pushing rods 12 abut.

10 20 A swinging arm 14 is provided on each one of the two arms of the balance beam 3, which arm 14 carries a weight 13. A spring catch 15 retains the swinging arm 14 when disposed at an acute angle to the vertical direction.

25 25 The spring catch 15 is linked to a check arm 18, which is controlled by a spring 17, by means of an angle lever 16. The hook-shaped end 20 of a latch 21 extending from a bolt 22 locks the extension 19 of the check arm 18. The nose 23 of the bolt 22 rests on a pawl 24, which is disposed on the arm 25 of a compensation weight 26 (see Fig. 2). The arm 25 together with the weight 26 is mounted in the frame 2 on the pivot 27 and slides in a curved guide 28. The pawl 24 is equipped with a compensation weight 30 opposite its tooth 29. The arms 31 of the pawl 24 are covered by a counter support 32. The bolt 22 is connected to one end of a draw spring 22', the other end of which is secured to a bracket 45 of the balance beam 3. The bracket 45 carries also the spring 17 for the check arm 18.

30 35 The arms 31 of the pawl 24 are covered by a counter support 32. The bolt 22 is connected to one end of a draw spring 22', the other end of which is secured to a bracket 45 of the balance beam 3. The bracket 45 carries also the spring 17 for the check arm 18. A lever 34 is secured to the supporting bolt 33 for the swinging arm 14, which lever 34 enters a slot 35 of the pushing rod 12 by means of a pin. One arm of an angle lever 38

40 45 slides in a slot 37 of an angle lever 36 which is also pivoted on the supporting bolt 33. The other arm of the angle lever 38 is disposed between two extensions 39 of a sliding rod 40 which slides along the balance wheel 3. The sliding rod 40 has at its ends cam members 46 which contact double levers 47, the latter being under pressure of springs (not shown), which double levers 47 are pivotally secured to frame posts 41. The nose-shaped ends 48 of the double levers 47 abut against the arms 39 of the discharge valves 6.

The frame posts 41 carry inclined planes 42 which are disposed at times within the swinging range of the weights 13 and of the latches 21 which are equipped with sideward extending fingers 43 and 44.

Piston rods 50 which lead to the pistons 51 are secured to the balance beam 3 at both sides of the pivot 1. The pistons 51 reciprocate in conventional manner in pump cylinders 52 which are connected to suction tubes 53. The latter are equipped with valves 54. Tubes 55 branch off the pump cylinders 52, which tubes 55 lead to a chamber 56. The tubes 55 are equipped with reduction cocks 57. The piston rods 50 have links 58, against which abutting members 59 of the balance beam 3 press, just before the end position of the balance beam 3 is reached. Springs 60 are provided to return the piston rods 50 to their straight position.

A cylinder 61, in which a piston 62 reciprocates, extends from the chamber 56. The piston rod 63 of the piston 62 leads to a receiver 64 which is surrounded by an angle lever system 65. The angle levers are connected with sliding rails 66, to which the curved guides 28 for the weights 26 are secured.

Counterweights 67 control the piston rod 63 by means of bars 68 which are secured to the frame. A bar 70 rests on an extension 69 of the piston rod 63, which bar 70 leads to a valve 71 of an over pressure pipe 72, which branches off the water feed pipe 73.

The present hydraulic device operates in the following manner:

In the position of the balance beam 3 shown in Fig. 1 the water container 4 is filled from the feeding tube 10 through the now open valve 9, while water which may be found in the lowered water container 5 is discharged. When the container 4 is completely filled, it has an overweight over the weight 26 and the latter is raised on its pivot 27, as indicated in point-dotted lines in Fig. 2. By this movement the pawl 24 frees the tooth 21 of the bolt 22. The balance beam 3 is lowered on the right side (Fig. 1) while its left side is raised. At the same time the pushing rod 12 is lowered, thereby closing the valve 9. Upon lifting the empty water container 5, its discharge valve 6 will also close.

The pump with its pistons 51 is operated by the movement of the balance beam 3. The water passing through the suction pipes 53 is fed into the chamber 56 and pressed into the feed tube 73.

A short time before the container reaches the lowest level, the abutting member 59 exerts pressure towards the link 58 of the piston rod 50. The latter collapses partly and the corresponding piston 51 remains at its place. The thus freed forces bring about, upon further lowering of the balance beam 3, first a raise of the weight 13 by means of the inclined plane 42 and then the lifting of the latch 21 from the extension 19 of the check arm 18 (see left side of Fig. 1). The empty lifted water container 5 reached in the meantime the position below the feed outlet 8. When the water container 5 performs the lifting movement, the coordinated bolt 22 contacts the pawl 24. The bolt 22 is, thereby, turned and the latch 21 rests behind the extension 19 of the check member 18, so that upon return movement of the bolt 22 the weight 13 is freed over the latch 21, the check member 18, the angle lever 16 and the spring catch 15. The feeding valve 9 is, thereby, opened by means of the pushing rod 12. Upon turning of the weight the an-

4
gular lever 38 is turned also. The extensions 39 of the sliding rod 40 bring about the sliding of the latter. One of the cam members 46 abuts against the double lever 47 and opens the discharge valve 6 in the lowered water container 4 by means of the arm 49.

In case the chamber 56 receives a very high pressure due to closing the feeding tube 73, the piston 62 is raised. At the same time the receiver 64 which rests on the piston rod 63 is lifted. The angular levers are moved sideward and simultaneously move the sliding rail 66 and the balancing weight 26, so that an overweight is reached only with a greater amount of water. The valve 71 for the over-pressure pipe 72 is then opened by means of the extension 69 and the bar 70 due to the lifting of the piston rod 63.

While I have disclosed one embodiment of the present invention, it is to be understood that this embodiment is given by example only and not in a limiting sense, the scope being determined by the objects and the claims.

I claim:

1. In an hydraulic device, a frame, a pivot on said frame, a balance beam supported by said pivot, a pump having a reciprocating piston disposed on each side of said pivot, piston rods of said pumps connected to arms of said balance beam, a water container having discharge valves supported adjacent each end of said balance beam, a water feeding tube having a feeding outlet for each of said containers, said water containers being positioned below the corresponding feeding outlet in their raised position, each of said feeding outlets having a feeding valve, and means for controlling said valves by the movement of said balance beam caused by the overweight of a container filled with water, and a regulating rod disposed along said balance beam, a swinging arm disposed on each arm of said balance beam, each of said swinging arms carrying a weight, means for coupling said swinging arm with said regulating rod and for moving said regulating rod in longitudinal direction, and said coupling means including means for opening the feeding outlet for the raised water container and the discharge valve of the lowered water container.

2. In an hydraulic device, a frame, a pivot on said frame, a balance beam supported by said pivot, a pump having a reciprocating piston disposed on each side of said pivot, piston rods of said pumps connected to arms of said balance beam, a water container having discharge valves supported adjacent each end of said balance beam, a water feeding tube having a feeding outlet for each of said containers, said water containers being positioned below the corresponding feeding outlet in their raised position, each of said feeding outlets having a feeding valve, and means for controlling said valves by the movement of said balance beam caused by the overweight of a container filled with water, said piston rods include link members permitting collapse of said piston rods, and an abutment member on each side of said balance beam, adapted to bring about collapse of said piston rods a short time before reaching the respective end positions of the balance beam.

3. In an hydraulic device, a frame, a pivot on said frame, a balance beam supported by said pivot, a pump having a reciprocating piston disposed on each side of said pivot, piston rods of said pumps connected to arms of said balance beam, a water container having discharge valves

supported adjacent each end of said balance beam, a water feeding tube having a feeding outlet for each of said containers, said water containers being positioned below the corresponding feeding outlet in their raised position, each of said feeding outlets having a feeding valve, and means for controlling said valves by the movement of said balance beam caused by the over-weight of a container filled with water, and an air chamber connected with the respective cylinders of said pumps, another cylinder extending from said air chamber, a reciprocating piston having a piston rod in said other cylinder, said last mentioned piston rod carrying adjustable weights, means for counterbalancing said water containers, and means for controlling said counterbalancing means by said last mentioned piston rod.

4. The device, as set forth in claim 3, which

includes a pressure tube extending from said air chamber, an overpressure tube branching off said pressure tube, a valve in said overpressure tube, and means for controlling said last mentioned valve by means of said last mentioned piston rod.
